UNITED STATES PATENT OFFICE.

HENRY PHILLIP KRAFT, OF RIDGEWOOD, NEW JERSEY; EDGAR J. PHILLIPS AND EARL A. DARR EXECUTORS OF SAID HENRY PHILLIP KRAFT, DECEASED.

WATER-BOTTLE STOPPER.

Application filed February 10, 1923, Serial No. 618,202. Renewed December 16, 1923.

This invention relates to stoppers for water bottles or other receptacles, and aims to provide certain improvements therein.

The invention is particularly directed to 5 ward a cheap and efficient form of stopper which shall have the necessary strength and rigidity, and which shall form an adequate closure for the hot water bag or other device to which it is applied. It also provides 10 certain other improvements which may be advantageously availed of, and which will be hereinafter more fully described.

In the drawings, wherein I have shown the preferred form of the invention,—

15 Figure 1 is a diametrical section of the upper part of a hot water bag, showing the invention as applied thereto.

Fig. 2 is a similar section of a stopper member of the type shown in Fig. 1, on a 20 larger scale, and provided with a swivel packing.

Fig. 3 shows the adaptation of the swivel packing to the conventional type of stopper.

Referring first to Fig. 1, let A indicate the 25 hot water bag or other receptacle, and B a socket member usually formed of sheet metal and having an inwardly turned flange C which constitutes in effect the valve seat against which a leak-tight joint is made by 30 the packing washer of the stopper.

The stopper proper according to the present invention comprises a cup D, closed at its bottom, and open at its top. The invention provides the standard form of wire 35 handle E, such as is used on more expensive types of stoppers, the handle in the present instance being carried down through the cup of the stopper and joined to the bottom F thereof. The joint may be made in 40 any approved fashion, but I prefer to rivet the ends of the wire to the bottom wall by perforating the bottom wall and countersinking the hole so that the ends of the wire when riveted, as shown at G, may be 45 flush with the under side of the bottom wall. It is advantageous to provide enlargements or flanges H which rest on the top of the bottom wall, so that a better connection may be made between the handle and the stopper.

50 In the preferred form of the invention, I provide a washer holder J which best comprises a tapered plate, having a flange underlying the washer K, the plate J being held in position by a projection L formed 55 in the bottom wall. Originally, the pro-

jection is substantially cylindrical, but is flattened down into slightly tapered form to engage the tapered inner wall of the plate.

By this construction a very satisfactory and efficient form of stopper is made at very 60 little expense. The cup, of which the stopper is formed, is made preferably of thin sheet metal, and its side walls are provided with rolled threads to engage the threads of the socket member B. It will be understood that the resistance to the screwing in of the stopper is primarily near the point of contact between the packing and seat, and the arrangement of the handle with its engagement at the lower wall of the stopper 65 enables the force of screwing the stopper to be applied as nearly as possible at the point of greatest resistance, without having to be transmitted through the side walls of the stopped. This permits a reduction of the 70 necessary thickness of the stopper, so that the whole construction, while strong and rigid, can be made of very thin gauge metal. In Fig. 2 I have illustrated the stopper with a swivel connection. In this case the metal 75 E' is riveted to the bottom wall F', as before, but the projection L is omitted from the cup. Around the outer edge of the cup is formed a groove M, in which is turned the edge of a swivel plate N, which carries the 80 packing washer. The swivel plate is provided with a projection L', entering the aperture in a plate J', which retains the packing washer K'. By this construction a broad, flat, bearing face is made with the 85 plate N, while the loose fit between the in-turned flange M and the groove of the cup permits a free and adequate swivelling. This feature of the invention is not necessarily limited to the construction shown in 90 Fig. 2, since it may be applied to other forms of stopper, as for instance, that illustrated in Fig. 3, where it shows the standard or conventional type of stopper.

While I have shown and described several 95 forms of the invention, it will be understood that I do not wish to be limited thereto, since various changes may be made therein without departing from the spirit of the invention.

100 What I claim is:—

1. A stopper for hot water bottles or the like, comprising a cup open at its top and a handle passing downwardly through the 105 open top end and connected with the cup 110

solely by engagement with the bottom wall thereof.

2. A stopper for hot water bottles or the like, comprising a cup formed of sheet metal and having a screw-threaded side wall, and a bottom, and a wire handle passing downwardly through the cup and said bottom wall and riveted to the latter.

3. A stopper for hot water bottles or the like, comprising a cup formed of sheet metal, the side wall of which is screw-threaded, and said cup having a bottom wall, a wire handle passing downwardly through the cup and riveted to said bottom wall, and a packing carried by the bottom of the stopper.

4. A stopper for hot water bottles or the like, comprising a cup formed of sheet metal having a closed bottom and an exterior groove in its side wall, a plate having its edge turned into said groove and swivelling with regard to the cup, and a packing carried by said plate.

5. A stopper for hot water bottles or the like, comprising a body member having an exterior groove in its side wall, a plate having its edge turned into said groove and

swivelling with regard to the body of the stopper, a packing carried by said plate, a tapered plate overhanging said packing, said tapered plate having a groove, and a projection on said first-named plate entering the groove in said tapered plate and holding the latter connected to the former.

6. A stopper for hot water bottles or the like, comprising an open cup formed of sheet metal and having a closed bottom wall, a wire handle having flanges resting on the top of said bottom wall, the ends of said handle passing through said bottom wall and being riveted on the opposite side of said wall to said flanges, said cup having a groove in its side wall, a swivelled plate contacting with said bottom wall, and having its edge turned into said groove, a tapered plate carried by said swivelled plate, said tapered plate having a lateral flange, and a packing located between the swivelled plate and the flange of said tapered plate.

In witness whereof, I have hereunto signed my name.

HENRY PHILLIP KRAFT.
